UNITED STATES PATENT OFFICE

CHARLES DOERING, OF CHICAGO, ILLINOIS

DESIGN FOR A PORTABLE LIQUID DRINK DISPENSER

Application filed July 25, 1932. Serial No. 44,441. Term of patent 14 years.

To all whom it may concern:

Be it known that I, CHARLES DOERING, a citizen of the United States, and a resident of the city of Chicago, in the county of Cook and State of Illinois, whose post office address is 1375 West Lake Street, Chicago, Illinois, have invented a new, original, and ornamental Design for a Portable Liquid Drink Dispenser, of which the following is a specification, reference being had to the accompanying drawing forming a part thereof.

I claim:

The ornamental design for a portable liquid drink dispenser substantially as shown.

CHARLES DOERING.
